BROOCH AND THE LIKE

Wilhelm Goetz, Providence, R. I., assignor to
 C. & G. Manufacturing Company, Inc., Providence, R. I., a corporation of Rhode Island

Application April 7, 1936, Serial No. 73,085

11 Claims.

(Cl. 63—20)

My invention relates to brooches and similar articles purposed to detachably carry one or more ornamental clips or clasps upon a base.

Heretofore it has been attempted to secure the clip, which included an ornamental face plate and a pivoted lever, by forming in the supporting plate one or more openings, together with numerous predetermined perforations. The lever or levers were then passed through the opening or openings and clamped against the back of the plate, the prongs upon the tongue during the clamping operation passing forwardly through the perforations.

The formation of the perforations involved exact and, therefore, expensive workmanship, and the exposure of the lever upon the back of the plate invited accidental tripping of the former and resultant accidental escape of the clip.

It is an object of this invention to overcome the disadvantages above adverted to.

Further objects of invention are to provide such means for attaching each clip to the supporting plate as will be facile to operate, secure, and inexpensive.

With the above and other objects in view, all of which will fully appear in the course of the following description, my invention consists in such parts and in such combinations of parts as fall within the scope of the appended claims.

In the accompanying drawing which forms a part of this specification and in which is shown merely a preferred form of embodiment of my invention,

Figures 1 and 2 are a front elevation and rear elevation respectively of a brooch embodying my invention,

Figure 3, a section of the same taken on lines 3—3 of Figure 2, partly in bottom plan,

Figure 4, a section taken on line 4—4 of Figure 2,

Figure 5, a front view of the supporting plate,

Figure 6, a section taken on line 6—6 of Figure 5, and

Figure 7, a perspective view of one of the clips in distended position.

Similar reference characters indicate similar parts throughout the views.

In the form of my invention herein illustrated a supporting or back plate 10 of thin sheet metal has equidistant from its central portion, integral with its top edge, forwardly and transversely directed U shaped flanges or gripping members 11 and 11' respectively. At each side of its central portion are two downwardly directed cut out por-

tions 12 whereby are formed pairs of similarly directed resilient arms 13 and 14 and 13' and 14' respectively. The arms 13 and 13' have integral with their ends forwardly directed identically formed lugs 15 and 15' respectively, each with its end edge beveled as at 16 and each provided with a lateral cam edge 17 extending from its end to a lateral cavity 18. The arms 14 and 14' have likewise forwardly directed terminal lugs 20 and 20' respectively in longitudinal alignment with the first mentioned lugs, and having their end edges beveled as at 21.

Upon extended end portions of the back plate 10 are the joint 22 and catch 23 of a pin tongue 24 for convenient engagement with a garment.

Detachably supported by the plate 10 are two clips or clasps 25 and 25'. As these clips are identical in construction in the present instance, a description of one will serve for both.

Each clip comprises an ornamental face plate 26 of any preferred configuration or design, and this plate constitutes one of the two clamping members of the clip. The second clamping member of each clip consists of a flat lever 28 including a forwardly inclined terminal tongue 29 having lateral trunnions or pivot members 30 passing loosely through perforations 31 in vertical ears 32 soldered or otherwise fixed to the rear portion of the face plate of the clip. A flat or leaf spring 34 in the path of the tongue 29 has open end slots 35 for the loose reception of the ears 32. The lever 28 is provided with attaching prongs 37. By virtue of the actuation of the lever spring 34 by the tongue 29, the lever 28 is impelled into snug closed position or into open position as the lever swings past its pivotal center in opposite directions.

When assembled the clips 25 and 25' are in closed position and the adjacent inner ends of their respective face plate 26 abut against each other forming in appearance a single symmetrical ornament, while the levers 28 of the clips bear against the front of the back plate 10. The upper and lower edges of each lever 28, as shown in Figure 7, is provided near its inner ends, transversely opposite each other, with elongated recesses 39 forming resultant shoulders 40 at the ends of the latter.

To engage a clip with the back plate one of the gripping flanges of the latter is drawn downwardly into overlapping engagement with the edge of the lever 28 in the upper recess 39 of the clip, and the plate and clip are then manually compressed towards each other which causes the lug 15 or 15' with its adjacent lug 20 or 20' to

- enter with a degree of friction the lower recess of the lever 28 assisted by their respective beveled terminal edges, and the plate is locked therein by reason of the entrance of the adjacent shoulder 40 of the lever into the cavity 18 of the latch member, of which it forms a part, after travelling over the cam edge 17. The resilience of the latch member permits this snapping engagement.
- 10 When it is desired to disengage either clip from the back plate the end margin of the clip to be removed is grasped by the thumb and finger of the operator and given a slight twist while the plate and second clip are being held stationary between the thumb and finger of the other hand.
- 15 The detachable character of the clips make it possible to employ my device as a brooch when the clips are mounted thereon, where the face plates form a symmetrical ornament. When, however, it is desired to use one or more clips temporarily as a clip per se upon an article of wearing apparel, such clip or clips may be detached from the back plate for that purpose with facility, and may be reengaged whenever desired with equal facility.
- 20 The back plate 10 is free of predetermined or other perforations as both the face plates and the levers of the clips are wholly in front of the back plate, and therefore there is no occasion for either
- 25 the lever 28 or its prongs 37 to pass through the back plate.
- 30 The flanges and latch members maintain the clips against the back plate, and added security is afforded by the presence of the recesses 39 in the lever 28.
- 35 I claim:
1. In an article of jewelry, a back plate, a clip wholly in front of the back plate, and resilient means integral with the back plate for maintaining the clip in contact with the front of the back plate.
2. In an article of jewelry, a back plate, garment attaching means upon the rear of the plate, two clips with abutting inner ends wholly in front
- 40 of the back plate, and means integral with the back plate for detachably engaging the clips.
- 45 3. In an article of jewelry, a back plate, a clip wholly in front of the back plate, and a latch member upon the back plate detachably engaging the clip.
- 50 4. In an article of jewelry, a back plate, a clip wholly in front of the back plate abutting against the back plate, a gripping flange upon the back plate engaging one portion of the clip, and a latch member upon the back plate detachably engaging an opposite portion of the clip.
- 55 5. In an article of jewelry, a back plate, a clip including a lever abutting against the front of the back plate, a flange upon the back plate engaging one lateral edge of the lever, an arm upon the plate disposed transversely of the flange, and a
- 60 forwardly directed lug upon the free end of the

arm adapted to frictionally engage the opposite edge of the lever.

6. In an article of jewelry, a back plate, a clip including a lever abutting against the front of the back plate, a flange upon the back plate engaging one lateral edge of the lever, a latch member including a transversely disposed arm upon the back plate, and a forwardly directed lug upon the free end of the arm engageable with the edge of the lever opposite the first mentioned edge. 10

7. In an article of jewelry, a back plate, a clip including a lever abutting against the front of the back plate, a flange upon the back plate engaging one lateral edge of the lever, a latch member comprising a resilient arm upon the back plate, 15 and a forwardly directed lug upon the free end of the arm engageable with the edge of the lever opposite the first mentioned edge, the forward portion of the lug being provided with a bevel.

8. In an article of jewelry, a back plate, a clip including a lever abutting against the front of the back plate, a flange upon the back plate engaging one lateral edge of the lever, a latch member including a resilient arm upon the back plate, a forwardly directed lug upon the arm provided 25 with a lateral cavity and with a cam face extending from the end of the lug to the cavity, said cavity being adapted to receive the opposite edge of the lever.

9. In an article of jewelry, a back plate, two 30 clips longitudinally disposed adjacent each other including levers in contact with the front of the back plate, flanges upon opposite sides of the central portion of the plate integral with the upper portion of the plate engaging one lateral edge of 35 each of the levers, two arms upon one side of the center of the plate, terminal lugs upon the two arms engageable with the second lateral edges of the levers, and two arms upon the side of the center of the plate opposite that of the first two 40 arms, and lugs upon the last two arms also engaging the second lateral edges of the levers.

10. In an article of jewelry, a back plate, a clip including a lever contacting with the front of the back plate provided with oppositely disposed recesses in its side edges, a flange upon the back plate engaging the lever in one recess, a latch member including a yielding arm integral with the back plate and a cam lug upon the arm engageable with the lever in the second recess, a 45 second arm integral with the plate adjacent the first arm, and a lug upon the second arm registerable in the second recess.

11. In an article of jewelry, a back plate, two 50 clips arranged with abutting inner ends and disposed longitudinally upon the back plate, means upon one lateral edge of the plate for gripping the adjacent lateral portion of the clips, and transversely disposed interspaced latch members upon the plate adapted to engage the lateral portions of the clips opposite the first mentioned lateral portions.

WILHELM GOETZ.
